US0D1105400S

(12) **United States Design Patent** (10) **Patent No.:** **US D1,105,400 S**
(45) **Date of Patent:** **** Dec. 9, 2025**

(54) **FOLDING FAN**

(71) Applicant: **E. MISHAN & SONS, INC.**, New York, NY (US)

(72) Inventor: **Mohan Rajasekaran**, Watertown, CT (US)

(73) Assignee: **E. MISHAN & SONS, INC.**, New York, NY (US)

(**) Term: **15 Years**

(21) Appl. No.: **29/989,116**

(22) Filed: **Feb. 10, 2025**

(51) LOC (15) Cl. **23-04**
(52) U.S. Cl. **USPC D23/382**

(58) **Field of Classification Search**

USPC D23/332, 333, 370, 378, 380, 381, 382,
D23/383
CPC F04D 25/08; F04D 25/084; F04D 25/0673;
F24F 2221/38

See application file for complete search history.

(57) **CLAIM**

The ornamental design for a folding fan as shown and described.

DESCRIPTION

FIG. 1 is a front top left perspective view of a folding fan showing my design;

FIG. 2 is a left view thereof;

FIG. 3 is a right view thereof;

FIG. 4 is a front view thereof;

FIG. 5 is a rear view thereof;

FIG. 6 is a top plan view thereof; and,

FIG. 7 is a bottom plan view thereof.

The broken dash-dot lines represent portions of the folding fan that form no part of the claimed design. The broken dash-dot lines represent boundaries of the folding fan that enclose areas that form no part of the claimed design.

1 Claim, 7 Drawing Sheets
